[57] CLAIM

The ornamental design for a bingo-card holder, as shown and described.

DESCRIPTION

FIG. 1 is a perspective view of a bingo-card holder, showing my new design;

FIG. 2 is a side-elevational view of the side not seen in
FIG. 1;

FIG. 3 is a bottom-plan view thereof;

FIG. 4 is a rear-elevational view thereof; and

FIG. 5 is a front-elevational view, showing the design in a folded position.

FIG. 1

FIG. 3

FIG. 4

FIG. 5

FIG. 2
